UNITED STATES PATENT OFFICE.

CHARLES T. WHITESCARVER AND GEORGE BENDIXEN, OF NEW YORK, N. Y.

SPREADER TIE FOR CONCRETE-WALL FORMS.

Application filed February 19, 1927. Serial No. 169,576.

This invention relates to improvements in spreader ties for concrete wall forms.

The primary object of the invention resides in a concrete form spreader tie for holding the form sections in rigid spaced relation and which facilitates the quick setting up and taking down of said sections.

Another object of the invention resides in a spreader tie in which certain elements of the same are left in the concrete wall structure, after the wall has been formed and the form sections removed therefrom to serve as a reinforcement for the wall.

A further object of the invention is to provide a spreader tie which is simple in construction, inexpensive of manufacture and highly efficient for the purpose intended.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a vertical sectional view through a wall form with my improved spreader tie in position thereon.

Figure 2 is a vertical transverse sectional view on the line 2—2 of Figure 1.

Figure 3 is a perspective view of the spreader tie per se.

Figure 4 is a vertical sectional view through a portion of a concrete wall structure with the form removed.

Referring more particularly to the drawing, the reference numeral 10 designates a concrete wall form which includes wall sections 11 and 12, each of which comprises vertical beams 13 to which horizontal boards 14 are fastened.

Our improved spreader tie is designated in its entirety as at 15 and comprises a brace member 16 constructed of flat metal twisted between its ends as at 17. The ends of the member are bent at right angle to the longitudinal axis of the body of the same to provide ears 18 through which the inner ends of a pair of rods 19 extend. The rods 19 extend through the vertical beams 13, boards 14, ears 18 and through horizontal cross beams 20, which cross beams are supported by said rods. The ends of the rods are screw threaded as at 21 and 22 respectively and co-acting with the screw threads

21 are corrugated cone members 23, which abut the inner faces of the form sections and the ears 18. Square nuts 24 also co-act with the screw threads 21 and are prevented from rotation by the flat face of the brace member 16.

For clamping the parts in position, we apply wing nuts 25 to the outer threaded ends 22 of the rods and which nuts are screwed home against the horizontal beams 20.

After the concrete has been poured into the concavity formed by the form sections and set, the said sections are removed by unscrewing the outer wing nuts 25 and turning the rods 19 to unthread the nuts 24 and corrugated cone members 23. The rods are then withdrawn and the form sections removed from against the wall. The brace member 16 and nuts 24 remain embedded in the wall structure as shown in Figure 4 of the drawing and act to reinforce the wall. The corrugated cone members 23 will also remain in the wall as the form sections are removed but the same are pried loose from the cement wall and the cone shaped recesses 80 formed thereby, are filled with cement so as to conceal the brace member and to impart a flat finished appearance to the wall structure. By making the member corrugated, the walls of the recesses formed thereby are correspondingly corrugated to more readily anchor the cement filler in place. It might be mentioned that the brace member 16 is twisted to strengthen the same and to provide an irregular contour to the 90 same so that water will not easily seep through from one side of the wall to the other.

What is claimed as new is:—

1. A concrete form spreader tie comprising a flat twisted brace member, removable rods extending from opposite ends of said brace member, corrugated cone members mounted on said rods and abutting the ends of said brace member, and clamping means 95 on said rods substantially as and for the purpose specified.

2. In combination with a pair of concrete form sections, a brace bar interposed between said sections, angularly disposed ears 105 on the ends of said brace bars, rods removably connected to said ears, said rods extending through the respective form sections, cone shaped members on said rods and interposed between said ears and said form 110

sections, and clamping elements carried by the outer ends of said rods substantially as and for the purpose specified.

3. A concrete form spreader tie comprising a twisted brace bar having ears on the ends thereof, a pair of rods having threaded ends, the inner ends of the rods extending through said ears, nuts threaded on the inner ends of said rods and prevented

from rotation by said brace bar, cone shaped members mounted on said rods, and clamping nuts co-acting with the outer threaded ends of said rods substantially as and for the purpose specified. 10

In testimony whereof we hereby affix our 15 signatures.

CHARLES T. WHITESCARVER.
GEORGE BENDIXEN.
